US00D843665S

(12) **United States Design Patent** (10) **Patent No.:** **US D843,665 S**
(45) **Date of Patent:** **** Mar. 19, 2019**

(54) **PET FEEDER**

(71) Applicant: **Shenzhen ChuangxinShangpin Technology Co., Ltd.**, Shenzhen (CN)

(72) Inventor: **Li Zeng**, Shenzhen (CN)

(73) Assignee: **Shenzhen ChuangxinShangpin Technology Co., Ltd.**, Shenzhen (CN)

(**) Term: **15 Years**

(21) Appl. No.: **29/630,006**

(22) Filed: **Dec. 18, 2017**

(51) LOC (11) Cl. **30-07**

(52) U.S. Cl.

USPC **D30/122**

(58) **Field of Classification Search**

USPC .... (57) **CLAIM**

A new, original, ornamental design for a pet feeder, as shown and described.

DESCRIPTION

FIG. 1 is a perspective view of a pet feeder showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

1 Claim, 7 Drawing Sheets
